Primary Examiner — Nyca T Nguyen*(74) Attorney, Agent, or Firm* — QuickPatents; Kevin Prince(57) **ABSTRACT**

A fitness bar system for use with exercise equipment, such as standard weights, Olympic weights, flat resistance bands, chains, tubular resistance bands, or the like, includes at least one elongated fitness bar having two opposing ends, each end being open and having an internal thread. At least one elongated cylindrical connector has two opposing ends, a threaded outside surface, and a plurality of threaded diametrical through holes each having threads. At least one adapter is fixable with the ends of each elongated fitness bar or with the ends of each of the elongated cylindrical connectors. The at least one adaptor is configured for connecting the fitness bar system with the exercise equipment. Multiple of the elongated fitness bars may be mutually connected with the elongated cylindrical connectors to form a fitness bar of several desired length.

MULTI-USE FITNESS BAR SYSTEM

CROSS-REFERENCE TO RELATED APPLICATIONS

This application claims the benefit of U.S. Provisional Patent Application 63/284,234, filed on Nov. 29, 2021, and is incorporated herein by reference.

STATEMENT REGARDING FEDERALLY SPONSORED RESEARCH AND DEVELOPMENT

Not Applicable.

FIELD OF THE INVENTION

This invention relates to exercise equipment, and more particularly to a multi-use fitness bar.

BACKGROUND

When performing fitness exercises, the use of a fitness bar is frequently required. Such a fitness bar is typically a metallic rigid rod or pole onto which weights or resistance bands are applied. Different exercises may require a different size fitness bars or connection mechanisms in order to be performed. However, it is impractical to purchase a single bar for each type of exercise required. Further, splitting a bar into multiple sections has weakened prior art fitness bars at their joints.

Therefore, there is a need for a fitness bar device that is easily configurable into different lengths as desired for particular exercises, all while maintaining the strength of the fitness bar. Such a needed invention would provide for various adapters easily attachable to the fitness bar, each adapter suited for use with specific types of exercise equipment, such as Olympic weights and various types and styles of resistance bands. The present invention accomplishes these objectives.

SUMMARY OF THE INVENTION

The present device is a fitness bar system for use with exercise equipment, such as standard weights, Olympic weights, flat resistance bands, chains, tubular resistance bands, or the like. A person may utilize the fitness bar system in isolation, or connected with another piece of exercise equipment, such as an exercise machine, via the resistance bands, for example.

The fitness bar system includes at least one elongated fitness bar having two opposing ends, each end being open and having an internal thread. In some embodiments, the at least one elongated fitness bar includes a knurled outer surface.

The fitness bar system further includes at least one elongated cylindrical connector having two opposing ends, a threaded outside surface, and a plurality of threaded diametrical through holes each having threads. In some embodiments the at least one elongated cylindrical connector has a standard diameter of about one inch for receiving sports equipment that takes the form of standard weights. As such, multiple of the elongated fitness bars may be mutually connected with the elongated cylindrical connectors to form a fitness bar of several different lengths.

At least one adapter is fixable with the ends of each elongated fitness bar or with the ends of each of the

2

elongated cylindrical connectors. The at least one adaptor is configured for connecting the fitness bar system with the exercise equipment. For example, the at least one adapter may include an Olympic weight adapter for receiving Olympic weights that have a diameter of about two inches. The at least one adapter may include at least one threaded collar configured for threadably engaging each of the at least one elongated connectors. Such a threaded collar includes a transverse aperture therethrough that is alignable with any of the diametrical through holes of each elongated cylindrical connector. At least one flat band hook or chain eyelet, each having a threaded shaft, may further be included, each configured for threadably connecting with both the transverse aperture of the at least one threaded collar and any of the diametrical through holes of the at least one elongated cylindrical connector. Each flat band hook is configured for receiving the flat-type resistance band, and each chain eyelet is configured for receiving a chain or a tubular resistance band.

In some embodiments, the at least one adapter includes an adjustable resistance band buckle configured for securing one end of the flat resistance band therein at a desired point selected by the person. The adjustable resistance band buckle has a top end that is adapted for securing with the at least one elongated cylindrical connector, through either a first transverse aperture or a second transverse aperture.

The present invention is a fitness bar system that is easily configurable into different lengths as desired for particular exercises, all while maintaining the strength of the fitness bar. The present system provides for various adapters easily attachable to the fitness bar, each adapter suited for use with specific types of exercise equipment, such as Olympic weights and various types and styles of resistance bands. Other features and advantages of the present invention will become apparent from the following more detailed description, taken in conjunction with the accompanying drawings, which illustrate, by way of example, the principles of the invention.

DESCRIPTION OF THE DRAWINGS

FIG. 1 is a perspective view of the invention;

FIG. 2 is a partial side perspective view of the invention, 45 illustrated with a threaded collar adapter fixed with a flat band hook;

FIG. 3 is a partial perspective view of the threaded collar adapter fixed with the flat band hook for use with flat resistance bands;

FIG. 4 is a partial perspective view of the threaded collar adapter fixed with a chain eyelet for use with chains or tubular resistance bands;

FIG. 5 is a partial exploded perspective view of an adjustable resistance band buckle type adapter for use with flat resistance bands having two opposing ends;

FIG. 6 is an exploded perspective view of the fitness bar system and several components thereof;

FIG. 7 is a perspective view of the fitness bar with the threaded collars and the flat band hooks;

FIG. 8 is a perspective view of the fitness bar with the adjustable resistance band buckle type adapter and the flat resistance band having two opposing ends;

FIG. 9 is an enlarged perspective view of one of an elongated cylindrical connectors of the invention;

FIG. 10 is a partially exploded perspective view of the invention, illustrating an Olympic weight adapter for use with Olympic style weights; and

FIG. 11 is a perspective view showing two rotational connector adapters each fixed with one of the flat band hooks and used with a flat resistance band.

DETAILED DESCRIPTION OF THE PREFERRED EMBODIMENT

Illustrative embodiments of the invention are described below. The following explanation provides specific details for a thorough understanding of and enabling description for these embodiments. One skilled in the art will understand that the invention may be practiced without such details. In other instances, well-known structures and functions have not been shown or described in detail to avoid unnecessarily obscuring the description of the embodiments.

Unless the context clearly requires otherwise, throughout the description and the claims, the words "comprise," "comprising," and the like are to be construed in an inclusive sense as opposed to an exclusive or exhaustive sense; that is to say, in the sense of "including, but not limited to." Words using the singular or plural number also include the plural or singular number respectively. Additionally, the words "herein," "above," "below" and words of similar import, when used in this application, shall refer to this application as a whole and not to any particular portions of this application. When the claims use the word "or" in reference to a list of two or more items, that word covers all of the following interpretations of the word: any of the items in the list, all of the items in the list and any combination of the items in the list. When the word "each" is used to refer to an element that was previously introduced as being at least one in number, the word "each" does not necessarily imply a plurality of the elements, but can also mean a singular element.

FIGS. 1-6 illustrate a fitness bar system 10 for use with exercise equipment 20, such as standard weights (not shown), Olympic weights 22, flat resistance bands 23, chains 24, tubular resistance bands (not shown), or the like. A person 30 may use the fitness bar system 10 in isolation, or connected with another piece of exercise equipment 20, such as an exercise machine (not shown), via the resistance bands 23, for example.

The fitness bar system 10 includes at least one elongated fitness bar 40 having two opposing ends 45, each end 45 being open and having an internal thread 49. Such an elongated fitness bar 40 is preferably made from a strong and rigid metal material, such as steel. In some embodiments, the at least one elongated fitness bar 40 includes a knurled outer surface 48.

The fitness bar system 10 further includes at least one elongated cylindrical connector 50 (FIG. 9) having two opposing ends 55, a threaded outside surface 59, and a plurality of threaded diametrical through holes 60 each having threads 65. Preferably each elongated cylindrical connector 50 includes five of the diametrical through holes 60 spaced evenly therealong. In some embodiments the at least one elongated cylindrical connector 50 has a standard diameter of about one inch for receiving sports equipment 20 that takes the form of standard weights (not shown). Preferably each elongated cylindrical connector 50 is made from a strong metallic material, such as steel. Multiple of the elongated fitness bars 40 may be mutually connected with the elongated cylindrical connectors 50 to form a fitness bar of several different, desired lengths.

At least one adapter 70 is fixable with the ends 45 of each elongated fitness bar 40 or with the ends 55 of each of the

elongated cylindrical connectors 50. The at least one adaptor is configured for connecting the fitness bar system 10 with the exercise equipment 20.

In preferred embodiments of the invention, the at least one adapter 70 includes an Olympic weight adapter 80 (FIGS. 1 and 10) for receiving sports equipment 20 that takes the form of Olympic weights 22 that have a diameter of about two inches. A locking collar 85 is configured for selectively retaining the Olympic weights 22 on the Olympic weight adapter 80. A mechanical fastener 170, such as a bolt or screw, secures the locking collar 85 to one of the diametrical through holes 60 of one of the elongated cylindrical connectors 50.

In preferred embodiments of the invention, the at least one adapter 70 further includes at least one threaded collar 110 configured for threadably engaging each of the at least one elongated connectors 50. Such a threaded collar 110 includes a transverse aperture 115 therethrough that is alignable with any of the diametrical through holes 60 of each elongated cylindrical connector 50. As such, exercise equipment 20 in the form of standard weights (not shown) can be held onto the fitness bar system 10 and restrained by each threaded collar 110.

Further, at least one flat band hook 120 having a threaded shaft 125 can be included, configured for threadably connecting with both the transverse aperture 115 of the at least one threaded collar 110 and any of the diametrical through holes 60 of the at least one elongated cylindrical connector 50. Each flat band hook 125 is configured for receiving exercise equipment in the form of the flat-type resistance band 23 (FIG. 7). In addition, a chain eyelet 130 having a threaded shaft 135 is included that can be threadably connected with both the transverse aperture 115 of the at least one threaded collar 110 and any of the diametrical through holes 60 of the at least one elongated cylindrical connector 50. Such a chain eyelet 130 is configured for receiving the exercise equipment 20 in the form of a chain 24 or of a tubular resistance band (not shown) as is known in the art.

Preferably the fitness bar system 10 further includes two fitness bar end caps 90, each configured for threading onto either end 55 of each of the elongated cylindrical connectors 50. Each fitness bar end cap 90 includes internal threads 99 adapted for cooperating with the threaded outer surface 59 of the at least one elongated cylindrical connector 50. In some embodiments each fitness bar end cap 90 includes an end aperture 95 therethrough, and in such embodiments two elastomeric or plastic caps 100 are included for selectively sealing the end aperture 95 by insertion into the fitness bar end caps 90 before the fitness bar end caps 90 are screwed onto the elongated cylindrical connectors 50.

In some embodiments, one or more of the elongated cylindrical connectors 50 includes a threaded longitudinal bore 140 at each end thereof, each longitudinal bore 140 having threads 145. As such, the at least one flat band hook 120 or one of the chain eyelets 130 can be threadably connected with the bore 140 of the at least one elongated cylindrical connector 50. In some embodiments, the at least one adapter 70 may include a rotational connector 160 (FIG. 11) such that the flat band hook 125 can hang downwardly relative to the elongated fitness bar 40 held horizontally.

In some embodiments, the at least one adapter 70 includes an adjustable resistance band buckle 150 (FIG. 5) configured for securing one end 26 (FIG. 8) of the flat resistance band 23 therein at a desired point selected by the person 30. The adjustable resistance band buckle 150 has a top end 158 that is adapted for securing with the at least one elongated cylindrical connector 50, through either a first transverse

aperture 157 (FIG. 8), or a second transverse aperture 156. Preferably each adapter 70 is made from a strong metallic material, such as steel or iron.

While a particular form of the invention has been illustrated and described, it will be apparent that various modifications can be made without departing from the spirit and scope of the invention. Accordingly, it is not intended that the invention be limited, except as by the appended claims.

Particular terminology used when describing certain features or aspects of the invention should not be taken to imply that the terminology is being redefined herein to be restricted to any specific characteristics, features, or aspects of the invention with which that terminology is associated. In general, the terms used in the following claims should not be construed to limit the invention to the specific embodiments disclosed in the specification, unless the above Detailed Description section explicitly defines such terms. Accordingly, the actual scope of the invention encompasses not only the disclosed embodiments, but also all equivalent ways of practicing or implementing the invention.

The above detailed description of the embodiments of the invention is not intended to be exhaustive or to limit the invention to the precise form disclosed above or to the particular field of usage mentioned in this disclosure. While specific embodiments of, and examples for, the invention are described above for illustrative purposes, various equivalent modifications are possible within the scope of the invention, as those skilled in the relevant art will recognize. Also, the teachings of the invention provided herein can be applied to other systems, not necessarily the system described above. The elements and acts of the various embodiments described above can be combined to provide further embodiments.

All of the above patents and applications and other references, including any that may be listed in accompanying filing papers, are incorporated herein by reference. Aspects of the invention can be modified, if necessary, to employ the systems, functions, and concepts of the various references described above to provide yet further embodiments of the invention.

Changes can be made to the invention in light of the above "Detailed Description." While the above description details certain embodiments of the invention and describes the best mode contemplated, no matter how detailed the above appears in text, the invention can be practiced in many ways. Therefore, implementation details may vary considerably while still being encompassed by the invention disclosed herein. As noted above, particular terminology used when describing certain features or aspects of the invention should not be taken to imply that the terminology is being redefined herein to be restricted to any specific characteristics, features, or aspects of the invention with which that terminology is associated.

While certain aspects of the invention are presented below in certain claim forms, the inventor contemplates the various aspects of the invention in any number of claim forms. Accordingly, the inventor reserves the right to add additional claims after filing the application to pursue such additional claim forms for other aspects of the invention.

What is claimed is:

1. A fitness bar system for use with exercise equipment, comprising:
at least one elongated fitness bar having two opposing ends, each end being open and having an internal thread;
at least one elongated cylindrical connector having two opposing ends, a threaded outside surface, and a plurality of diametrical through holes each with threads;

at least one adapter fixable with the ends of either the at least one elongated fitness bar or the at least one elongated cylindrical connector, the at least one adapter configured for connecting the fitness bar system with the exercise equipment,

wherein the at least one elongated fitness bar has a standard diameter for receiving sports equipment that takes the form of standard weights, and wherein the at least one adapter includes an Olympic weight adapter for sports equipment that takes the form of Olympic weights, the Olympic weight adapter including a locking collar configured for selectively retaining the Olympic weights on the Olympic weight adapter.

2. The fitness bar system of claim 1 wherein the at least one elongated fitness bar includes a knurled outer surface.

3. The fitness bar system of claim 1 wherein the at least one elongated cylindrical connector includes five of the diametrical through holes spaced evenly therealong.

4. A fitness bar system for use with exercise equipment, comprising:

at least one elongated fitness bar having two opposing ends, each end being open and having an internal thread;

at least one elongated cylindrical connector having two opposing ends, a threaded outside surface, and a plurality of diametrical through holes each with threads; at least one adapter fixable with the ends of either the at least one elongated fitness bar or the at least one elongated cylindrical connector, the at least one adapter configured for connecting the fitness bar system with the exercise equipment;

two fitness bar end caps each configured for threading onto either end of each of the elongated cylindrical connectors.

5. The fitness bar system of claim 4, wherein each fitness bar end cap includes an end aperture therethrough.

6. The fitness bar system of claim 5 further including elastomeric caps configured for frictionally fitting into each fitness bar end cap to occlude the end aperture of the fitness bar end cap.

7. A fitness bar system for use with exercise equipment, comprising:

at least one elongated fitness bar having two opposing ends, each end being open and having an internal thread;

at least one elongated cylindrical connector having two opposing ends, a threaded outside surface, and a plurality of diametrical through holes each with threads; at least one adapter fixable with the ends of either the at least one elongated fitness bar or the at least one elongated cylindrical connector, the at least one adapter configured for connecting the fitness bar system with the exercise equipment;

wherein the at least one adapter includes at least one threaded collar configured for threadably engaging each of the at least one elongated cylindrical connector and having a transverse aperture therethrough alignable with any of the diametrical through holes of each elongated cylindrical connector, whereby exercise equipment in the form of standard weights is configured to be held onto the fitness bar system and restrained by each threaded collar.

8. The fitness bar system of claim 7 further including at least one flat band hook having a threaded shaft adapted for threadably connecting with both the transverse aperture of the at least one threaded collar and any of the diametrical through holes of the at least one elongated cylindrical

connector, each flat band hook configured for receiving exercise equipment in the form of a flat-type resistance band.

9. The fitness bar system of claim 7 further including at least one chain eyelet having a threaded shaft adapted for threadably connecting with both the transverse aperture of the at least one threaded collar and any of the diametrical through holes of the at least one elongated cylindrical connector, each chain eyelet configured for receiving exercise equipment in the form of a chain or a tubular resistance band.

10. A fitness bar system for use with exercise equipment, comprising:

at least one elongated fitness bar having two opposing ends, each end being open and having an internal thread;

at least one elongated cylindrical connector having two opposing ends, a threaded outside surface, and a plurality of diametrical through holes each with threads;

at least one adapter fixable with the ends of either the at least one elongated fitness bar or the at least one elongated cylindrical connector, the at least one adaptor configured for connecting the fitness bar system with the exercise equipment;

wherein each elongated cylindrical connector has at each end thereof a longitudinal bore with threads.

11. The fitness bar system of claim 10 further including at least one flat band hook having a threaded shaft adapted for threadably connecting with the bore of the at least one elongated cylindrical connector, each flat band hook configured for receiving exercise equipment in the form of a flat-type resistance band.

12. The fitness bar system of claim 10 further including at least one chain eyelet having a threaded shaft adapted for

threadably connecting with the bore of the at least one elongated cylindrical connector, each chain eyelet configured for receiving exercise equipment in the form of a chain or a tubular resistance band.

13. A fitness bar system for use with exercise equipment, comprising:

at least one elongated fitness bar having two opposing ends, each end being open and having an internal thread;

at least one elongated cylindrical connector having two opposing ends, a threaded outside surface, and a plurality of diametrical through holes each with threads;

at least one adapter fixable with the ends of either the at least one elongated fitness bar or the at least one elongated cylindrical connector, the at least one adaptor configured for connecting the fitness bar system with the exercise equipment;

wherein the at least one adapter includes an adjustable resistance band buckle configured for securing one end of a flat resistance band therein at a desired point, the adjustable resistance band buckle having a top end adapted for securing with the at least one elongated cylindrical connector.

14. The fitness bar system of claim 13 wherein the top end of the adjustable resistance band buckle includes a first transverse aperture therethrough.

15. The fitness bar system of claim 14 wherein the top end of the adjustable resistance band buckle includes a second transverse aperture therethrough, the second transverse aperture orthogonal to the first transverse aperture.
